UNITED STATES PATENT OFFICE.

JOSEPH PIETZUCH, OF CINCINNATI, OHIO.

SHOE-HEEL CUSHION.

1,264,127.

Specification of Letters Patent. Patented Apr. 23, 1918.

Application filed March 7, 1917. Serial No. 153,050.

To all whom it may concern:

Be it known that I, JOSEPH PIETZUCH, a citizen of the United States of America, residing at Cincinnati, in the county of Hamilton, State of Ohio, have invented certain Improvements in Shoe-Heel Cushions, of which the following is a description, reference being had to the accompanying drawings, forming a part thereof.

10 The object of the invention is to provide means for correcting the position of the human foot in walking and remedying what is generally known as "flat foot" resulting from the falling of the inner or outer longitudinal arch, or the transverse arch of the foot, by equalizing the strains upon the foot, to relieve those portions of the foot structure which are overtaxed and cause other portions to assume their proper proportion 20 of the weight, said means being of such a simple and inexpensive character as to permit of the general use thereof and permit of application without the exercise of special skill to the ordinary walking shoe.

25 Further objects and advantages of the invention will appear in the following description of a preferred embodiment, it being understood that changes in the form, proportion and minor details may be 30 sorted to within the scope of the appended claims without departing from the spirit of the invention.

In the drawings,

Figure 1 illustrates one embodiment of 35 the invention applied in the operative position to a shoe.

40 Figs. 2 and 3 are plan views of a heel cushion embodying the invention and wherein varying ratios of areas of different coefficients of elasticity are illustrated.

Fig. 4 is a transverse sectional view of a cushion.

It is a well known fact that many if not all people throw more or less weight or 45 stress in walking either to the inside or the outside of the foot, as illustrated by the uneven wearing of the heels and also the soles of shoes, thereby indicating that an increased strain is thrown upon one side or 50 the other, and this indicates either a constitutional weakness of the inside or the outside arch of the foot, or a condition which will lead to the breaking down of the longitudinal arches or of the transverse arch or 55 both, resulting in a complaint which is ordinarily termed "flat foot" which destroys the

elasticity or springiness of the gait, not to speak of more or less serious personal inconvenience or distress.

The use of resilient or elastic heels or 60 heel cushions to relieve the shock or jar in walking is well known but owing to the uniformity of elasticity throughout the surface of the heel or cushion, the strains due to the causes above noted are not relieved, and the 65 wear on the heel progresses unevenly or is accentuated more at one side than the other and therefore the weaker arch of the foot is not fortified, but on the other hand is used more or less at the expense of the stronger arch. 70

To correct this tendency, it is proposed to provide a composite heel or heel cushion such as that illustrated in Figs. 2 and 3 of the drawing hereto attached, wherein one section or member of the area, as indicated 75 at 10, is of a higher coefficient of elasticity or resiliency than the other section 11. For example, one section or member may be of seventy-five per cent. resiliency, whereby the section of the lower coefficient of elasticity 80 offers more resistance to wear and hence tends to throw the weight of the body in walking toward the other portion or section of the cushion which is of greater elasticity. Obviously the relative areas of these sections may 85 be varied to suit the conditions or the seriousness of the inequality of wear under normal conditions, either one-half of the entire area being of the lower coefficient of elasticity, as shown in Fig. 3, or approximately 90 two-thirds thereof being of either the higher or the lower coefficient of elasticity, as suggested in Fig. 2.

95 Preferably the cushion is constructed as a composite article, so that it may be applied to the heel of the shoe as a unit and in this event the selection of the proper cushion to suit a particular case or a particular shoe may be determined by the dealer or shoemaker upon inspection of the condition of 100 the shoe previously worn by the user.

Rubber of different degrees of resiliency as hard rubber and soft rubber may be employed in the construction of cushions in accordance with the invention, and it is contended in behalf thereof that the breaking down or falling of the foot arches may be prevented or corrected by the use thereof when properly applied in view of the normal position of the foot of the patient, the 110 weight being thrown either one way or the other, as circumstances may require to equal-

ize the pressure and the strains upon the foot arches.

What I claim is:

1. A rubber shoe heel cushion, formed of two sections and made integral, one section lying to the right and the other section to the left side of the heel and both approximately longitudinally disposed to form the tread area of the heel, one section being of greater resiliency and more yieldable than the other section.

2. A shoe heel cushion formed of sections

and made integral, each section having a definite and different degree of resiliency, said sections so disposed in the tread area of the heel that each section will partly lie at the border of said heel.

This specification signed and witnessed this 2 day of March, A. D. 1917.

JOS. PIETZUCH.
